Primary Examiner — Joseph Kukella*Assistant Examiner* — Heather Ann Laaveg Wencel(74) *Attorney, Agent, or Firm* — Studebaker & Brackett PC(57) **CLAIM**

The ornamental design for an operating panel for elevator, as shown and described.

DESCRIPTION

FIG. 1 is a perspective view of an operating panel for elevator, showing a first embodiment of my new design; FIG. 2 is a front view thereof; FIG. 3 is a rear view thereof; FIG. 4 is a left side view thereof; FIG. 5 is a right side view thereof; FIG. 6 is a top view thereof; FIG. 7 is a bottom view thereof; FIG. 8 is a partially enlarged view of FIG. 1; FIG. 9 is a reference view showing the state in use; FIG. 10 is a perspective view of an operating panel for elevator, showing a second embodiment of my new design; FIG. 11 is a front view thereof; FIG. 12 is a rear view thereof; FIG. 13 is a left side view thereof; FIG. 14 is a right side view thereof; FIG. 15 is a top view thereof; FIG. 16 is a bottom view thereof; FIG. 17 is a partially enlarged view of FIG. 10; and, FIG. 18 is a reference view showing the state in use. In the drawings, the broken lines depict environmental subject matter that forms no part of the claimed design.
